UNITED STATES PATENT OFFICE.

MAX STUPAR, OF BUFFALO, NEW YORK, ASSIGNOR TO ABRAHAM J. ELIAS, OF BUFFALO, NEW YORK.

DETACHABLE STABILIZING-FIN FOR FLYING-MACHINES.

1,350,948.

Specification of Letters Patent. Patented Aug. 24, 1920.

Original application filed June 25, 1919, Serial No. 306,613. Divided and this application filed December 10, 1919. Serial No. 343,751.

To all whom it may concern:

Be it known that I, MAX STUPAR, a citizen of the United States, residing at Buffalo, in the county of Erie and State of New York, have invented certain new and useful Improvements in Detachable Stabilizing-Fins for Flying-Machines, of which the following is a specification.

My present invention relates generally to heavier-than-air flying machines, and more particularly to hydroaeroplanes of the type described and claimed in my copending application, Serial Number 306,613, which was filed June 25, 1919, and of which the present application is a division.

The object of my present invention is the provision of a readily attachable and detachable stabilizing fin which will be rigidly supported in effective position and which, when detached, may be packed in minimum storage space.

In the accompanying drawings, illustrating my present invention and forming a part of this specification,

25 Fig. 1 is a side elevation of a hydro-aeroplane provided with my present invention,

Fig. 2 is a rear elevation of a portion of the tail structure,

30 Fig. 3 is a partial side elevation of the rear portion of the stabilizing fin and the tail post,

Fig. 4 is a rear elevation of the tail post, and

35 Fig. 5 is a cross section through the upper portion of the fuselage adjacent to the forward end of the stabilizing fin, taken on line 5-5 of Fig. 1.

Referring now to these figures, and particularly to Fig. 1, I have shown a hydro-aeroplane comprising a fuselage 10, tail structure generally indicated at 11, wings 12 and pontoons 13.

40 The stabilizing fin proposed by my present invention is seen at 14, disposed flatwise in its operative position upon the upper rear portion of the fuselage 10, and has at each side of its forward portion, a depending hinged and apertured locking leaf 15 engageable with a laterally projecting rigid locking stud 16 at the respective side of the rear portion of the fuselage 10. The rear end of this stabilizer has at a central point a rearwardly projecting rigid stud 17 which,

in attaching the stabilizer in place, is extended through the upwardly projecting apertured extension 18 of the tail post fitting 19 of the fuselage 10, as seen in Fig. 3.

From this latter figure and Fig. 4, it will also be noted that the tail post 19 is securely fastened to the rear end of the fuselage 10 and has at its lower side portions oppositely projecting side ears 19^a apertured to receive locking pins 20 detachably connecting the lower ends of the upwardly and outwardly projecting stabilizer braces 21. These braces are in the form of a pair of struts whose outer ends are connected to the lower surfaces of the rear side portions of the stabilizing fin 14 as particularly seen in Fig. 2. 70

Thus to disconnect and remove the stabilizing fin, it is simply necessary to release the locking pins 20 of its braces 21 and the locking pins utilized to hold the locking leaves 15 on the studs 16. Thereupon the 75 stabilizing fin as a whole may be shifted forwardly and its rear stud withdrawn from the upper opening of the tail post 19.

In packing the fuselage of an aeroplane and the like for transportation, it is obvious 80 considerable difficulty in crating will be avoided by removing the stabilizing fin and hence my improved fin with its ready adaptability in this direction is of striking importance, particularly as its reassembly upon 85 uncrating may be accomplished as quickly and with as little difficulty as its removal.

I claim:—

1. A flying machine including a fuselage having a tail post provided with an upper 90 apertured extension, a stabilizing fin having detachable connection at its forward portion with the fuselage, and a stud projecting from the central rear portion of the said fin and extending into the aperture of said tail 95 post.

2. A flying machine including a fuselage having a tail post provided with an upper extension, a stabilizing fin having means at its central rear portion detachably engaging 100 the said tail post extension, and means detachably connecting the forward portion of the said fin to the fuselage.

3. A flying machine including a fuselage a stabilizing fin having detachable connections at the sides of its forward portion and at the center of its rear portion to said fuselage, and braces connected at their outer 105

2
ends to the rear side portions of the stabilizing fin and having detachable connection at their inner ends with the fuselage.

4. A flying machine including a fuselage
5 having upper laterally outstanding locking
studs spaced from its rear end, a stabilizing
fin having detachable connection at its rear
end with the rear end of the fuselage, and
10 apertured hinged locking leaves carried by
the forward portion of said stabilizing fin

arranged to depend over the said locking
studs, as described.

5. A flying machine including a fuselage,
and a stabilizing fin seated horizontally on
the upper rear portion of the fuselage and 15
having detachable connection at the sides of
its forward and the center of its rear portion
with the fuselage.

In testimony whereof I affix my signature.
MAX STUPAR.
